(57) **CLAIM**

The ornamental design for a coil component, as shown and described.

DESCRIPTION

FIG. 1 is a front elevational view of a coil component, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, bottom perspective view thereof; and,

FIG. 8 is an enlarged front, right-side, bottom perspective partial view.

The broken lines depict parts of the coil component that form no part of the claimed design. The dot-dash broken lines define the bounds of the claimed design and form no part thereof.
